Primary Examiner—Alan P. Douglas*Assistant Examiner*—Caron D. Veynar*Attorney, Agent, or Firm*—Oblon, Spivak, McClelland, Maier & Neustadt[57] **CLAIM**

The ornamental design for an electronic copying machine, as shown and described.

DESCRIPTION

FIG. 1 is a perspective view showing an electronic copying machine with paper supply cassettes withdrawn and original cover opened, showing our new design;

FIG. 2 is a front elevational view thereof, with the cover and cassettes in the closed position;

FIG. 3 is a right side elevational view thereof;

FIG. 4 is a rear side elevational view thereof;

FIG. 5 is a left side elevational view thereof;

FIG. 6 is a top plan view thereof; and,

FIG. 7 is a bottom plan view thereof.

FIG. 3

FIG. 5

FIG. 4

FIG. 7

FIG. 6
